Ms. 580

John Mason of Providence R.I.
Assignor to
High Street Furnace Company of Providence R.I.
Letters Patent No 580. Dated July 19, 1853.

To all Persons to whom these Presents shall come:

Be it known that I John Mason of Providence, in the County of Providence, and State of Rhode Island have produced a new and original design for a cooking stove, and I hereby declare that the said new design is fully described and represented in the following specification and accompanying drawings, to which reference is hereinafter made.

The figures of the accompanying plates of drawings represent my new design. In Plate 1 fig 1. is an elevation of the side plate of the stove and fig 2. a section of the same taken in the plane of the line A B. fig 1. In Plate 2 fig 3. is an elevation of the front plate. In Plate 3. fig 4 is an elevation of the back plate.

The side plate fig 1. has around it the mouldings a.a. &c and across the top the raised flowers b.b. The oven door has around it the mouldings c.c. and is ornamented in the center with the twelve pointed figure composed of the raised leaves d. d &c, and raised spear heads e.e &c. The two smaller doors are each ornamented with the mouldings c.c. and

Wes. 50

eight pointed figures composed of small raised leaves d.d. and raised spearheads e.e. On the bottom and side of this plate are small raised leaves d.d. united together by the centre flower f.f.

The front plate fig. 3. has around it the mouldings a.a. and the doors have around them the mouldings c.c. The two lower doors are ornamented with the eight pointed figures composed of leaves d.d. and spear heads e.e. like those of the side plate, on the sides of the plate are two leaves d.d. united together by the flower f.f.

The back plate fig. 4. has around it the mouldings a.a. the side panels g.g. g.g. having around them the mouldings c.c. and each being ornamented with the two large raised leaves d.d. united together by a center flower h.h. The center panel i.i. has upon it the eight pointed figure composed of the large leaves d.d. &c. meeting at the center of the figure in the flower h.

Having thus described my new design I shall state my claim as follows.

What I claim as my invention or production and desire to have secured to me by Letters Patent is the new design consisting of the flower work and ornamental figures composed of the raised leaves and spear heads, as herein above described and represented in the drawings, for the front, side, and back plates of a cooking stove.
